[57] **CLAIM**

The ornamental design for a can end, as shown and described.

DESCRIPTION

FIG. 1 is a front top perspective view of our new design for a can end;

FIG. 2 is a top plan view of FIG. 1;

FIG. 3 is a bottom plan view of FIG. 1;

FIG. 4 is a side view of FIG. 1 (all side views correspond to FIG. 4);

FIG. 5 is a front top perspective view of a second embodiment of the can end of FIG. 1 showing the can tab in broken lines;

FIG. 6 is a top plan view of FIG. 5;

FIG. 7 is a bottom plan view of FIG. 5;

FIG. 8 is a side view of FIG. 5 (all side views correspond to FIG. 8); and

FIG. 9 is a front top perspective view of the can end of FIG. 5, shown in a final position of use when attached to a can body;

FIG. 10 is a top plan view of FIG. 9;

FIG. 11 is a side view of FIG. 9; and,

FIG. 12 is a fragmentary sectional view taken along the line 12—12 in FIG. 10.
